FURNACE

Bernard Goerg, Scarsdale, N. Y., assignor, by
mesne assignments, to American Radiator &
Standard Sanitary Corporation, New York,
N. Y., a corporation of Delaware

Application October 21, 1937, Serial No. 170,172

15 Claims. (Cl. 126—242)

This invention relates to furnaces, and more particularly to an improved means for disposing of the ash in furnaces of the type having grate bars supported for ash-shaking movement and an ash pit arranged beneath the grate bars and receiving the ash falling from said grate.

The invention consists in the novel construction and combination of parts, to be more fully described hereinafter, and the novelty of which will be particularly pointed out and distinctly claimed.

In the accompanying drawings, to be taken as a part of this specification, I have fully and clearly illustrated a preferred embodiment of my invention, in which—

Fig. 1 is a view partially in side elevation and partially in transverse vertical section, showing a furnace constructed in accordance with the present invention;

Fig. 2 is a fragmentary vertical section taken on the line 2—2 of Fig. 1 and showing by dot-and-dash lines the relative position of the ash-removal opening which is in the furnace front wall and in front of the plane of the section;

Fig. 3 is a fragmentary plan section taken on the line 3—3 of Fig. 1;

Fig. 4 is a fragmentary vertical section taken on the line 4—4 of Fig. 3; and

Fig. 5 is a fragmentary view showing in perspective the movable ash-deflecting member.

Referring now in detail to the construction illustrated, it will be observed that I show my invention as incorporated in a boiler furnace, indicated in general by the reference character 10, and comprising a rectangular fuel-supporting grate 11 dividing the interior of the furnace into a combustion chamber 12 and an ash pit 13. The combustion chamber 12 is shown as being defined by vertically arranged boiler sections 14 disposed in side-by-side relation. The ash pit 13 is defined by a front wall 15, a rear wall 16, and side walls 17 and 18 joining the ends of the front and rear walls. The boiler sections 14 are supported by the upper edges of the front, rear and side walls of the ash pit. The entire structure is inclosed by a suitable jacket 20, and a suitable heat insulating material 21 is provided between the jacket 20 and the sections 14.

The ash pit 13 comprises a main portion 22 centrally disposed beneath the grate 11 and co-extensive therewith, and a pair of pockets or spaces 23 and 24 at the sides thereof and adjacent the side walls 17 and 18, respectively. The spaces 23 and 24 are offset laterally from

the adjacent sides, respectively, of the grate 11 and extend from the front wall 15 to the rear wall 16. The front wall 15 is provided with a rectangular ash-removal opening 25 which, as shown, may be approximately centrally disposed with respect to the grate 11 and of substantially the same width as the grate 11, or slightly less in width, if desired. The shape and size of the opening 25 can best be seen in Fig. 2 by the dot-and-dash lines. The opening 25 is adapted to be closed by a hinged door 25a.

The grate 11 comprises a plurality of substantially parallel grate bars 26 arranged side-by-side and extending in the same direction as the front and rear walls 15 and 16. The grate bars 15 26 are supported at their ends for rocking or oscillatory movement about substantially parallel axes. To this end, each of the grate bars 26 is provided at its opposite ends with aligned trunnion pockets 27 which receive, respectively, 20 and are supported by aligned grate trunnions 28 extending inwardly from the upper edge of the side walls 17 and 18.

Each grate bar is provided with an operating crank arm 30 which depends from the end of 25 the grate bar which is adjacent the side wall 17 and into the space 23, hereinafter referred to as the grate-operating space 23. Each crank arm is provided with a crank pin 31 extending away from the grate 11 and towards the side 30 wall 17. The crank arms 30 are preferably of the same length and size and the crank pins 31 are arranged in substantially the same horizontal plane when the grate bars 26 are in their center position, the position shown on the drawings.

The grate bars 26 are adapted to be rocked back and forth about their axes by manual means. To this end, a grate connecting bar 33 extends longitudinally of the grate-operating 40 space 23 and is supported for lengthwise reciprocatory movement by suitable openings (not shown) extending through the front and rear wall 15 and 16, respectively. The bar 33 is provided with a series of vertically elongated 45 openings or slots 34 extending therethrough, equal in number to and spaced the same distance apart as the crank pins 31. The pins 31 extend, respectively, through the openings 34, and when the bar 33 is manually reciprocated, 50 as will presently appear, the pins 31, arms 30 and grate bars 26 are caused to oscillate or rock about their respective trunnion supports to shake the ashes from the fuel bed supported by the grate.

The bar 33 extends through the front and rear walls 15 and 16, and means is provided externally of the furnace for manually reciprocating the grate bars for the purpose aforementioned. While the manual means may be connected either to the forward or to the rearward extension of the bar 33 without departing from the present invention, I have elected to show the manual means as connected to the forward extension (see Fig. 1). The forward end of the bar is connected by a pin 35 with a vertical lever 36. The lower end of the lever is fulcrumed by a pin 37 carried by a bracket 38 fixed to the front wall 15, and the upper end 15 of the lever is adapted to be grasped by the hand for movement backward and forward toward the front wall 15, such movement resulting in reciprocatory movement of the bar 33, as will be readily understood. It is to be noted 20 that it is not necessary for the lever to be located in line with the bar 33, because the lever could equally as well be located at the side of the furnace. In the latter case, any suitable motion-transmitting devices would be provided for 25 connecting the lever 36 and bar 33.

In order to facilitate the removal of ashes from the furnace and to eliminate the scattering of ashes and dust in the basement, I provide an ash pan 40 which is here shown to be approximately centrally arranged in the ash pit and directly beneath the grate 11, and is adapted to receive the ashes as they fall through the grate. The ash pan is of slightly less width than the opening 25 to permit its manual insertion 30 and removal therethrough, and is of substantially the same dimensions as the grate 11 and the main portion 22 of the ash pit.

It is of course desirable that the ash pan be as large as possible in order to receive all 40 of the ashes falling through the grate. In other words, it would be desirable to have the ash pan as wide as the ash pit so as to assure that all the ash falling from the outer edges of the grate would enter the pan. This is impractical, however, due to the fact that the width of the ash pan 40 is limited by the width of the opening 25, and the width of the latter is limited by the structural strength requirements of the defining wall through which the opening 25 extends 50 which is the front wall 15. The width of the opening 25 is also limited by other structural reasons, such as the design and location of the grate-shaking mechanism and the hinge support for the ash door 25a. From a practical view 55 point, the opening 25 cannot be much wider than the grate, unless the wall through which the opening 25 extends be substantially wider than that shown, and such a construction as the latter would involve other structural changes which 60 would affect the general design, cost and appearance of the entire structure.

In order to assure that ash falling from the edges of the grate will enter the pan, I provide 65 ash-deflecting means above and around the four sides of the pan which cause such ash to move laterally into the pan. This deflecting means comprises a deflecting plate 42 extending along and fixed to the rear wall 16 and having an inclined deflecting surface 43 overhanging the adjacent edge of the pan 40, a deflecting plate 44 70 extending along and fixed to the side wall 18 and having an upper deflecting surface 45 closing off the space 24 and overhanging the adjacent upper edge of the pan 40, and a deflecting 75 plate 46 extending along and fixed to the

ash pit door 25a which closes the ash removal opening 25 and having an upper ash-deflecting surface 48 overhanging at its lower edge the front edge of the pan. Along the remaining edge of the pan 40 which is adjacent the grate-operating space, the problem cannot be met by a rigidly secured deflector plate, such as the plates 42, 44 and 46, due to the fact that the movable grate-operating means occupies this space. 5

In order to assure that ash falling from the 10 edge of the grate adjacent the grate-operating edge 23 is deflected laterally into the pan, I provide an ash-deflecting device 50. The device 50 comprises a supporting plate member 51 extending longitudinally of the grate-operating space and having a substantially flat upper supporting surface 52 and an outer longitudinal edge 53 overhanging the adjacent edge of the pan 40. The supporting plate is fixed to the side wall 17 by brackets 54 and bolts 55. The 20 ash-deflecting device 50 also comprises an element 56 extending longitudinally of the space 23 and slidably supported by that portion of the surface 52 which is remote from the pan 40. The element 56 is connected to the crank pins 31 for 25 movement therewith.

The element 56 is angle-shaped in cross section and comprises a horizontally extending supporting part 58 having its under surface in sliding engagement with the surface 52 and a vertically extending ash-shielding part 59 which is provided with a series of vertically elongated openings or slots 60 through which the crank pins 31 extend. The slots 60 are spaced apart the same distance as the crank pins, as shown. 30 35 Therefore, when the pins 31 are moved by the bar 33, the element 56 is moved back and forth longitudinally of the space.

The vertical part 59 provides a shield which 40 prevents ash from falling behind it. Ash collecting on the uncovered part of the surface 52 will be moved laterally across such surface and into the pan 40 by spaced V-shaped projections 61. In order to prevent ash from entering between the bearing portion of the surface 52 and 45 the under surface of the element 56 and working past the supporting part 58, the under surface of the part 58 is provided with a series of V-shaped notches 62 disposed side-by-side and opening toward the pan 40. Therefore, any 50 ash tending to enter between the bearing surfaces will be deflected toward the pan 40 by the inclined edges of the notches 62.

It is to be noted that, while I have elected to disclose in one preferred embodiment the element 56 as being a separate part moved by the pins 31, in so far as the broader aspects of my invention are concerned, the element 56 may be secured to the bar 33 for movement therewith, or the element 56 and bar 33 may even be formed 60 as an integral piece.

From the above, it will be apparent that I have provided an improved form of furnace, wherein all of the ash falling from an ash-shaking grate falls into a pan, and the pan may be readily removed, the ashes emptied and the pan replaced with a minimum of dust and dirt in the basement. It will also be apparent that one of the main contributing factors to the beneficial new results attained by my construction is the 65 fact that I have provided deflecting means around the sides of the ash pit which provides for lateral movement of ash into the pan; and that this deflecting means includes as a part thereof, a deflecting device which is movable with 70 75

the grate-operating arms for deflecting the ash laterally into the adjacent side of the pan.

It is to be noted that all of the above results are accomplished by structure which is so designed and located that ready access may still be had to the ash pit in case it is desired to inspect, repair, or replace parts, or in case it is desired to remove the ashes by hand should the ash pan be damaged, deteriorated, or the like. It is for this latter reason that I prefer to secure the deflector plate 46 to the door 25a rather than to the stationary parts of the defining walls of the ash pit.

It is also to be noted that, while I have shown my invention as incorporated in a rectangular furnace of the boiler type, it is not to be considered as so limited in all of its aspects, for in so far as its broader aspects are concerned, it may be incorporated in any furnace having an ash-shaking grate and grate-operating elements depending from a side of the grate.

What I claim and desire to secure by Letters Patent of the United States is:

1. In combustion apparatus, the combination of means defining a furnace structure; a fuel-supporting grate dividing the furnace structure into a combustion chamber and an ash pit and including a plurality of similarly disposed grate bars supported for ash-shaking movement; grate-operating elements depending respectively from the ends of the grate bars at one side of the ash pit; a removable ash pan supported directly beneath the grate in ash-receiving position; and means arranged around the sides of the ash pit and above the ash pan for directing ash falling from the sides of said grate into said pan, and including an element movable with said grate-operating elements for moving ash laterally into said pan.

2. In a furnace, a fuel-supporting grate comprising a plurality of grate bars supported for ash-shaking movement; grate-operating arms depending from the grate along one side thereof and connected respectively to the grate bars for operating the latter; walls defining an ash pit beneath the grate and including a grate-operating space extending along the side of the grate from which the arms depend and receiving the latter; a removable ash pan arranged beneath the grate in position to receive ash falling therefrom and having a side extending in the same direction as the grate-operating space and adjacent thereto; and means in said grate-operating space for directing falling ash into the ash pan and including an element connecting said grate-operating arms and movable therewith for moving ash laterally into said pan.

3. In a furnace, a fuel-supporting grate comprising a plurality of grate bars supported for ash-shaking movement; a plurality of grate-operating arms depending respectively from the ends of the grate bars along one side of the grate; wall means defining an ash pit located beneath the grate and including a grate-operating space located below and extending along the side of the grate from which the arms depend; one of the defining walls of said ash pit having an ash-removal opening therein; an ash pan arranged within the ash pit beneath said grate and being of a width to permit its insertion and removal through said opening; and means arranged above and along the sides of said pan for deflecting the ashes falling from the edges of said grate laterally into said pan; said means including a supporting plate member arranged lengthwise of said grate-operating space and having a longi-

tudinal edge portion overhanging the adjacent upper edge of said pan, and including an ash-deflecting member slidably supported by said plate member and connected for movement with said grate-operating arms for moving ash laterally into said pan.

4. In a furnace, a fuel-operating grate comprising a plurality of grate bars supported for ash-shaking movement; grate-operating arms depending from the grate along one side thereof and connected respectively to the grate bars for operating the latter; walls defining an ash pit beneath the grate and including a grate-operating space extending along the side of the grate from which the arms depend and receiving the latter; a removable ash pan arranged beneath the grate in position to receive ash falling therefrom and having a side extending in the same direction as the grate-operating space and adjacent thereto; and means in said grate-operating space for deflecting falling ash laterally into the ash pan and comprising a supporting plate member extending longitudinally of said space and having a longitudinal edge overhanging said side of the ash pan, and an ash-deflecting member slidably supported by said plate member and connected for movement with said grate-operating arms for moving ash laterally into said pan.

5. In a furnace, a fuel-supporting grate comprising a plurality of grate bars supported for ash-shaking movement; grate-operating arms depending from the grate along one side thereof and connected respectively to the grate bars for operating the latter; walls defining an ash pit beneath the grate and including a grate-operating space extending along the side of the grate from which the arms depend and receiving the latter; a removable ash pan arranged beneath the grate in position to receive ash falling therefrom and having a side extending in the same direction as the grate-operating space and adjacent thereto; and means in said grate-operating space for deflecting falling ash laterally into the ash pan and comprising a supporting plate member extending longitudinally of said space and having a longitudinal edge overhanging said side of the ash pan, and an ash-deflecting member extending longitudinally of said space and being angle-shaped in cross section, with one side of the angle being slidably supported by said supporting plate member and the other side of said angle extending upwardly to form an ash shield and being connected for movement with said grate-operating arms.

6. In a furnace, a fuel-supporting grate comprising a plurality of grate bars supported for ash-shaking movement; grate-operating arms depending from the grate along one side thereof and connected respectively to the grate bars for operating the latter; walls defining an ash pit beneath the grate and including a grate-operating space extending along the side of the grate from which the arms depend and receiving the latter; a removable ash pan arranged beneath the grate in position to receive ash falling therefrom and having a side extending in the same direction as the grate-operating space and adjacent thereto; and means in said grate-operating space for deflecting falling ash laterally into said ash pan and comprising a stationary plate member extending longitudinally of said space and having a longitudinal edge overhanging said side of said pan and having a substantially flat upper supporting surface, and an ash-deflecting member extending longitudinally of said space and

- supported for lengthwise slidable movement on the part of said upper supporting surface which is remote from said pan, said ash-deflecting member being operatively connected to said 5 grate-operating arms for movement thereby and having elements projecting toward said pan for moving ash lodging on the uncovered part of said flat upper surface laterally across said uncovered surface and into said pan.
10. In a furnace, a fuel-supporting grate comprising a plurality of grate bars supported for ash-shaking movement; grate-operating arms depending from the grate along one side thereof and connected respectively to the grate bars for 15 operating the latter; walls defining an ash pit beneath the grate and including a grate-operating space extending along the side of the grate from which the arms depend and receiving the latter; a removable ash pan arranged beneath 20 the grate in position to receive ash falling therefrom and having a side extending in the same direction as the grate-operating space and adjacent thereto; and means in said grate-operating space for deflecting falling ash laterally into said 25 ash pan and comprising a stationary plate member extending longitudinally of said space and having a longitudinal edge overhanging said side of said pan and having a substantially flat upper supporting surface, and an ash-deflecting mem- 30 ber extending longitudinally of said space and supported for lengthwise slidable movement on the part of said upper supporting surface which is remote from said pan, said ash-deflecting member being operatively connected to said grate- 35 operating arms for movement thereby and having V-shaped elements projecting across the remaining part of said flat upper surface and toward said pan so as to deflect ash lodged on said surface into said pan.
40. In a furnace, a fuel-supporting grate comprising a plurality of grate bars supported for ash-shaking movement; grate-operating arms depending from the grate along one side thereof and connected respectively to the grate bars for operating the latter; walls defining an ash pit beneath the grate and including a grate-operating space extending along the side of the grate from which the arms depend and receiving the latter; a removable ash pan arranged beneath the grate 45 in position to receive ash falling therefrom and having a side extending in the same direction as the grate-operating space and adjacent thereto; and means in said grate-operating space for deflecting falling ash laterally into said pan; said 50 means comprising a stationary supporting plate member extending longitudinally of said space with one edge thereof overhanging said side of the pan and having an upper supporting surface, and an ash-deflecting member extending longitudinally of said space and having an under surface engaging the part of said upper surface which is remote from said pan for lengthwise sliding movement, one of said surfaces having a plurality of V-shaped notches formed therein and arranged side-by-side with their open side towards said pan so as to insure movement of ash from between said surfaces and toward said pan, and means connecting said ash-deflecting member to said grate-operating arms for movement thereby.
55. In a furnace, a fuel-supporting grate comprising a plurality of grate bars supported for ash-shaking movement; grate-operating arms depending from the grate along one side thereof and connected respectively to the grate bars for 60 operating the latter; walls defining an ash pit beneath the grate and including a grate-operating space extending along the side of the grate from which the arms depend and receiving the latter; a removable ash pan arranged beneath the grate and having a side extending longitudinally of said space and having an upper supporting surface, and an ash-deflecting member extending longitudinally of said space and having an under surface engaging the part of said upper surface which is remote from said pan for lengthwise sliding movement, one of said surfaces having a plurality of V-shaped notches formed therein and arranged side-by-side with their open side towards said pan so as to insure movement of ash from between said surfaces and toward said pan, and means connecting said ash-deflecting member to said grate-operating arms for movement thereby.
65. In a furnace, a fuel-supporting grate comprising a plurality of grate bars supported for ash-shaking movement; grate-operating arms depending from the grate along one side thereof and connected respectively to the grate bars for 65 operating the latter; walls defining an ash pit beneath the grate and including a grate-operating space extending along the side of the grate from which the arms depend and receiving the latter; a removable ash pan arranged beneath the grate and having a side extending longitudinally of said space and having an upper supporting surface, and an ash-deflecting member extending longitudinally of said space and having an under surface engaging the part of said upper surface which is remote from said pan for lengthwise sliding movement, one of said surfaces having a plurality of V-shaped notches formed therein and arranged side-by-side with their open side towards said pan so as to insure movement of ash from between said surfaces and toward said pan, and means connecting said ash-deflecting member to said grate-operating arms for movement thereby.
70. In a furnace, a fuel-supporting grate comprising a plurality of grate bars supported for ash-shaking movement; grate-operating arms depending from the grate along one side thereof and connected respectively to the grate bars for 70 operating the latter; walls defining an ash pit beneath the grate and including a grate-operating space extending along the side of the grate from which the arms depend and receiving the latter; a removable ash pan arranged beneath the grate and having a side extending longitudinally of said space and having an upper supporting surface, and an ash-deflecting member extending longitudinally of said space and having an under surface engaging the part of said upper surface which is remote from said pan for lengthwise sliding movement, one of said surfaces having a plurality of V-shaped notches formed therein and arranged side-by-side with their open side towards said pan so as to insure movement of ash from between said surfaces and toward said pan, and means connecting said ash-deflecting member to said grate-operating arms for movement thereby.
75. In a furnace, a fuel-supporting grate comprising a plurality of grate bars supported for ash-shaking movement; grate-operating arms depending from the grate along one side thereof and connected respectively to the grate bars for 75 operating the latter; walls defining an ash pit beneath the grate and including a grate-operating space extending along the side of the grate from which the arms depend and receiving the latter; a removable ash pan arranged beneath the grate and having a side extending longitudinally of said space and having an upper supporting surface, and an ash-deflecting member extending longitudinally of said space and having an under surface engaging the part of said upper surface which is remote from said pan for lengthwise sliding movement, one of said surfaces having a plurality of V-shaped notches formed therein and arranged side-by-side with their open side towards said pan so as to insure movement of ash from between said surfaces and toward said pan, and means connecting said ash-deflecting member to said grate-operating arms for movement thereby.

- having a side arranged directly adjacent said grate-operating space; a stationary supporting plate arranged lengthwise of said space and having a longitudinal edge overhanging said side of 5 said ash pan; and an ash-deflecting member extending lengthwise of said space and comprising a supporting part slidably supported by said plate, and an upwardly extending ash-shield part having spaced vertical slots therethrough receiving 10 respectively the crank pins, so that as the latter are oscillated the ash-deflecting part is moved lengthwise back and forth along the supporting plate and ash falling from the adjacent edge of the grate is deflected into said ash pan.
- 15 12. In a furnace, a fuel-supporting grate comprising a plurality of similarly extending grate bars supported for rocking movement about substantially parallel axes; crank arms depending from said grate along one side thereof and connected respectively at their upper ends to said 20 grate bars and each arm including a crank pin at its lower end extending away from said grate; upright walls defining an ash pit disposed below said grate; said ash pit including a main portion 25 directly beneath and coextensive with said grate and a grate-operating space offset laterally from the side of the grate from which the crank arms depend and receiving the latter; means connecting said crank pins and movable back and forth 30 lengthwise of said space for rocking said grate bars about their respective axes; a removable ash pan arranged beneath said grate and having a side arranged directly adjacent said grate-operating space; a stationary supporting plate arranged 35 lengthwise of said space and having a longitudinal edge overhanging said side of said ash pan; and an ash-deflecting member extending lengthwise of said space and comprising a supporting part slidably supported by the side 40 of said plate which is remote from said pan, an upwardly extending ash-shield part having spaced vertical slots therethrough receiving respectively the crank pins so that as the latter are oscillated the ash-deflecting part is moved lengthwise back and forth along said supporting plate, and spaced projections extending from said supporting part and towards said pan for moving ash laterally across said supporting plate and into said pan.
- 45 13. In a furnace, a fuel-supporting grate comprising a plurality of grate bars supported for ash-shaking movement; grate-operating arms depending from the grate along one side thereof and connected to the grate bars for operating 50 the latter; a removable ash receptacle arranged beneath said grate; a plate member extending lengthwise beneath the side of the grate from which said arms depend and having an outer edge overhanging said ash receptacle; and means movable with said grate-operating arms for moving ash from said plate member into said pan.
- 55 14. In a furnace, a fuel-supporting grate comprising a plurality of grate bars supported for ash-shaking movement; a plurality of grate-operating arms depending respectively from the ends of the grate bars along one side of the 60 grate and movable back-and-forth in the same general direction to impart ash-shaking movement to said bars; wall means defining an ash pit located beneath the grate and including a grate-operating space offset laterally from said grate and extending lengthwise along the side of the grate from which the arms depend for receiving the latter and extending in the same general direction as the direction of movement of the arms; a removable ash pan arranged beneath said grate 65 and for receiving the ash falling therethrough and including a side located adjacent to and extending in the same general direction as the grate-operating space; and ash deflecting means located in said grate-operating space and extending longitudinally thereof for deflecting any ash falling from the adjacent edge of said grate laterally into said ash pan; said last-named means comprising a wall member connected to said grate-operating arms for movement back-and-forth therewith and the wall member extending lengthwise of said space and providing an upright ash-shielding surface in said space and offset laterally from the adjacent side of said grate and facing the adjacent side of said ash pan.
- 70 15. In a furnace, a fuel-supporting grate comprising a plurality of grate bars supported for ash-shaking movement; a plurality of grate-operating arms depending respectively from the ends of the grate bars along one side of the grate and movable back-and-forth in the same general direction to impart ash-shaking movement to said bars; wall means defining an ash pit located beneath the grate and including a grate-operating space offset laterally from said grate and extending lengthwise along the side of the grate from which the arms depend for receiving the latter and extending in the same general direction as the direction of movement of the arms; a removable ash pan arranged beneath said grate 75 and for receiving the ash falling therethrough and including a side located adjacent to and extending in the same general direction as the grate-operating space; and ash deflecting means located in said grate-operating space and extending longitudinally thereof for deflecting any ash falling from the adjacent edge of said grate laterally into said ash pan; said last-named means comprising a wall member extending lengthwise of said space and including an upwardly extending ash-shielding surface facing said pan and a deflecting surface extending laterally from the ash-shielding surface towards said pan; means for supporting said wall member for reciprocatory motion lengthwise of said space; and means for connecting said wall member to said grate-operating arms so that as the grate-operating arms are operated, the wall member moves back-and-forth with said arms.
